United States Patent Office

Des. 196,828
Patented Nov. 5, 1963

196,828

HEATER

Judkins E. Wilkinson, Birmingham, Ala., assignor to
Atlanta Stove Works, Inc., a corporation of Georgia

Filed Apr. 24, 1962, Ser. No. 69,838

Term of patent 14 years

(Cl. D81—19)

FIG. 1 is a front isometric view of a heater showing my new design;

FIG. 2 is a front elevational view; and,

FIG. 3 is a rear isometric view.

The dominant features of my design reside in the portions shown in full lines, said portions being characterized by the front paneled members as shown in FIGS. 1 and 2.

I claim:

The ornamental design for a heater, as shown and described.
